UNITED STATES PATENT OFFICE.

ALBERT L. HALE, OF CHICAGO, ILLINOIS.

CLEANING AND POLISHING MACHINE.

SPECIFICATION forming part of Letters Patent No. 650,790, dated May 29, 1900.

Application filed December 29, 1897. Serial No. 664,395. (No model.)

To all whom it may concern:

Be it known that I, ALBERT L. HALE, of Chicago, county of Cook, and State of Illinois, have invented a new and useful Improvement in Means for Operating Tools upon Irregular Surfaces, of which the following is a specification.

My invention relates to machines for transmitting power for operating rotary brushes or abrading-tools for cleaning or polishing surfaces, driving drills, or other similar cutting-tools, but more especially for operating brushes or shears in grooming horses or other animals, my object being to provide a construction adapted to operate tools upon very irregular surfaces and in any direction, the same being described hereinafter and illustrated in the accompanying drawings; in which—

Figure 1 is a side elevation showing the machine as it appears when adapted to operate a rotary brush. Fig. 2 is an elevation at a right angle to what is shown Fig. 1 or in the direction indicated by arrow 8 of a shorter machine than is shown in Fig. 1 and with the brush or tool shaft broken away. Fig. 2^A is a plan below broken line 13 13 of Fig. 2. The broken lines 9, 10, 11, and 12 of Figs. 1 and 2 show angles out to which and beyond the machine may be swung laterally when necessary in reaching surfaces at different distances from the normal center line of the suspension-rod. Fig. 3 shows, respectively, a side and a front elevation of a hanger adapted to suspend the operative parts from the ceiling. Fig. 4 shows, respectively, a side and front elevation and a plan of a shaft and pulley frame which is pivotally mounted in the hanger shown in Fig. 3. Fig. 5 shows, respectively, a front and a side elevation of a yoke and a top portion of a suspension-rod attached thereto adapted to connect the parts hereinbefore described with an adjustable spring swivel device, which latter is shown in Fig. 6 on a larger scale than in the preceding figures. Fig. 6 shows the lower end portion of the suspension-rod, together with the lowest end portion of the rod, which is screw-threaded for a short distance and has screw-threaded nuts mounted thereon, and there are guide-pulleys mounted on a pivotally-attached frame and a horizontally-disposed

tool-driving shaft having one end mounted to revolve in said attached frame, all shown in elevation, while a helical spring and a portion of a swivel-frame and the tool-shaft-driving pulley, together with the casing for this shaft, are shown in axial section, indicated by the direction of broken line 14, Fig. 2, with the exception of the lower end of the swivel-yoke, Fig. 6, which is in elevation. The broken lines 15 and 16 of Fig. 6 indicate positions to which the tool-shaft may be swung to vertically, and a much greater angle may be reached, if necessary, in practice without materially interfering with the tension of the vertically-disposed driving-belt. Fig. 7 shows a flexible tool-shaft in elevation, with one end of an elastic covering therefor shown as it appears when slit longitudinally and opened to expose a helical-spring shaft within, which is adapted to connect the horizontally-disposed tool-shaft with the brush or other tool, as shown in Fig. 1.

The ceiling-hanger has two downwardly-projecting portions A and A', between whose lower ends the rectangular frame B is pivotally mounted to vibrate or swing on oppositely-disposed bolts B' and B''. At a right angle to these pivotal bolts are bosses on frame B, in which are secured the ends of a stationary cross-shaft C, Fig. 4, extending diametrically across frame B, and loosely mounted to revolve on the shaft is a pulley D, having a double groove to receive a driving and a driven belt for transmitting power, as herein-after described. At each end of the shaft C, close to frame B, the upper ends of the arms of a yoke E are mounted to easily swing thereon and to straddle the pulley D. At the lower end of yoke E is secured the upper end of a suspension-rod F, whose lower end terminates in a tail-rod having a portion next the suspension-rod at F' screw-threaded and with screw-threaded nuts mounted thereon.

The greater part of the lower portion of the tail-rod is cylindrical and is fitted to easily slide longitudinally and vertically in a hole in the top of a swivel-buckle G, the buckle also being adapted to revolve around the rod for the purpose hereinafter explained. A helical spring is mounted on the tail-rod and has bearing at the top against the nuts F' and at the bottom against the top of swivel-

buckle G, whereby the swivel-buckle is forced downwardly, but limited in its downward movement by the stop-pin F⁴, Fig. 6, contacting the under side of the head of the buckle. The lower end of the buckle G is pivotally attached to a pulley-frame H by means of a transverse bolt H', whose pivotal center is on the same line transversely as the pivotal centers of two pairs of belt-guide pulleys I J and K L, which are mounted at the sides near the top of frame H.

In the lower portion of frame H and at right angles to the pivotal center H' of buckle G is mounted the end of a horizontally-disposed revoluble shaft M, a grooved pulley N being secured thereto between the lower arms of the frame H. Pulley N is connected with pulley D at the ceiling-hanger by means of a round belt O, which passes up and down between the opposing pairs of guide-pulleys I and J and K and L. Shaft M in this instance is disposed within a tubular holder P, which has one end firmly secured to the pulley-frame H, so that its outer end may form a bearing for the outer end of shaft M, as shown at M², Fig. 6. Shaft M terminates in a screw M', in this instance, whereby a helical wire flexible shaft may be attached thereto by being screwed thereon, in the usual manner of attaching such shafts.

In Fig. 1 is shown a form of flexible shaft which is particularly adapted to use in transmitting power for machines of this class, and its novelty consists in covering the coils comprising the ordinary helical shaft with an elastic covering of india-rubber R in the form of a jacket, which in practice serves to yieldingly hold the coils of the shaft in proper position, whereby the shaft may be made to transmit much more power without undue vibration when bent at a sharp angle than can be attained by the same shaft with an ordinary inelastic covering.

Although the flexible shaft R' may be coupled to shaft M by being screwed onto the screw-threaded tenon M', as stated, there are other methods of coupling in common use which may be adopted for machines of this kind which revolve either way and which may be quickly uncoupled or coupled when intended for driving several different kinds of tools which are often changed.

At R² is a handle which is loosely mounted on a spindle R³, which forms the outer termination of flexible shaft R, which latter is usually directly coupled with any tool which is being operated, as shown in Fig. 1. Helical spring F³ is for the purpose of forcing the pulley-frame H and pulley N downwardly to yieldingly adjust or control the tension of belt O as it may lengthen by extended use or when under the strain of duty. The use of this tension device also prevents to a great degree an unskilled person fastening the belt with too great or too small a tension to properly operate the tool. By the use of this de-

vice it is not necessary to shorten the belt until by the increased length thereof the swivel-buckle G contacts with the stop-pin F⁴. (See Fig. 6.) The belt may be shortened until the adjusting-nuts F² are screwed up to the upward limit of the threaded portion F' of the tailpiece of the suspension-rod, the nuts being screwed downwardly from time to time as the belt becomes loose.

Ordinarily, in practice, a rotary motion is imparted to pulley D by means of a round belt in communication with some source of power, and motion is transmitted vertically downwardly to pulley N, shaft M, and the flexible tool-shaft R by means of round belt O, which is guided or held in line with the plane of rotation of pulley N by the pairs of pulleys I J and K L at opposite sides, as before stated.

The pivotal centers of suspension at the ceiling-hanger being placed relatively at right angles to each other, the suspension-rod F may be swung from the position shown laterally and upwardly in any direction, and since frame H is attached to swivel-buckle G by means of a horizontally-disposed pivotal center H' and the swivel-buckle is so mounted on tail-rod F that it may revolve entirely around in a horizontal plane it is obvious that shaft M may be swung around and upwardly in any direction necessary in connection with flexible shaft R to adapt the machine to operate tools upon surfaces subtending any angle to a vertical or horizontal plane, which particularly adapts it to use for grooming animals or for cleansing castings or objects of very irregular form.

I claim as my invention—

1. The combination, with a hanger, the projecting portions of which extend laterally and are perforated in a line with each other, of a frame journaled therein, the sides of which are raised and perforated in a line with each other, a wheel and a yoke journaled in said frame, the yoke being provided with a suspension-rod, a flexible shaft supported by the rod, the outer end of which is adapted to receive a tool, and a belt over the pulley in the frame and over the inner end of the shaft.

2. The combination, with a hanger-pulley, of a suspension-rod, a flexible shaft yieldingly supported by said rod, means for regulating and limiting the tension of the support, and a belt over the pulley and over the inner end of the shaft, the outer end of the shaft being adapted to receive a tool.

3. The combination, with a pulley, of a suspension-rod, the lower end of which is provided with a tail-rod, of a swivel-buckle on the tail-rod, a spring on the tail-rod in engagement with the buckle, means for regulating the tension of the spring, a flexible shaft journaled in the buckle, the outer end of which is adapted to receive a tool, and a belt over the pulley and over the inner end of the shaft.

4. The combination, with a pulley, of a suspension-rod, the lower end of which is screw-threaded and provided with a tail-rod, a nut on the screw-threads, a swivel-buckle on the tail-rod, a stop below the buckle, a spring between the nut and the buckle, a shaft journaled in the buckle, and a belt over the pulley and over the end of the shaft.
5. The combination, with a pulley, of a suspension-rod, a swivel-buckle supported by the rod, a frame pivotally secured to the buckle, a pair of guide-pulleys mounted in the frame on each side of said pivotal point and in a line therewith, a flexible shaft journaled below said guide-pulleys, the inner end of which is provided with a pulley in a line with the

guide-pulleys, and a belt over all of said pulleys.

6. The combination, with a pulley, of a suspension-rod provided with a swivel-buckle, an armed frame pivotally secured to the buckle, a pair of guide-pulleys journaled on each side of said pivotal point and in a line therewith, a shaft journaled in the arms, the outer end of which is provided with a shoulder, a pulley on the shaft between the arms, a belt over the pulleys, and a sleeve on the shaft between the frame and the shoulder.

ALBERT L. HALE.
